US00D725125S

(12) **United States Design Patent**
Capela et al.

(10) **Patent No.:** **US D725,125 S**
(b4) **Date of Patent:** **** Mar. 24, 2015**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jay Christopher Capela**, Cupertino, CA (US); **Markus Hagele**, Cupertino, CA (US); **Alexander Charles MacLean**, Cupertino, CA (US); **Charles Janusz Migos**, Cupertino, CA (US); **Roger Rock Rosner**, Cupertino, CA (US)

(73) Assignee: **Apple Inc.**, Cupertino, CA (US)

(**) Term: **14 Years**

(21) Appl. No.: **29/435,306**

(22) Filed: **Oct. 23, 2012**

(51) LOC (10) Cl. **14-04**

(52) U.S. Cl.

USPC **D14/485**

(58) **Field of Classification Search**

CPC G06F 3/048; G06F 3/0481; G06F 3/0482

USPC D14/485-495

(57) **CLAIM**

The ornamental design for a display screen or portion thereof with graphical user interface, as shown and described.

DESCRIPTION

The FIGURE is a front view of a display screen or portion thereof with graphical user interface showing our new design. The broken lines around the Figure showing a display screen or portion thereof form no part of the claimed design. The broken lines within the Figure show portions of the graphical user interface which form no part of the claimed design.

1 Claim, 1 Drawing Sheet
